[57] **ABSTRACT**

A wire drawing machine has a plurality of drawing dies each associated with a drawing block powered by a direct current electric motor, all the motors being connected in parallel and having current supply controlling circuitry which insures that the sum of all of the motor speeds are constant and that all torques are equal except for a proportionality factor.

PATENTED JUL 9 1974

3,822,575

NON-SLIP NON-ACCUMULATING CONTINUOUS WIRE DRAWING MACHINE

This invention relates to a non-slip non-accumulating continuous wire drawing machine with adjustable back-pull containing a number of drawing dies and drawing blocks, whereby each drawing block is driven by a direct current motor with external excitation and whereby the interconnection of the motors and the design of the control mechanism are such that the sum of the speeds of all motors remains constant and that, except for a proportionality factor, the torques connected to the motors remain equal to each other. Non-accumulating means that the wire is not pulled over transfer pulleys between the successive blocks in order to carry out speed regulations.

This invention also relates to other kinds of machines, such as hot and cold rolling mills, and so on. In the following description, a drawing machine is given as a particular example.

A wire drawing machine in accordance with the invention, also called wire drawing machine with differential drive, has important advantages, viz., automatical compensation for drawing die wear or changes in the mechanical efficiency over the complete speed range of the machine.

Therefore, the following requirements must be met:

1

a. the sum of the speeds of the various motors remains unchanged or

$$n_1 + n_2 + \dots + n_i + \dots + n_n = \text{constant} \quad (1)$$

b. the torques remain equal to each other except for a proportionality factor:

$$\begin{aligned} C_1 &= C_1 \\ C_2 &= k_2 C_1 \\ &\vdots \\ C_i &= k_i C_1 \end{aligned} \quad (2)$$

$$C_n = k_n C_1$$

Since externally excited current motors are used for driving the various blocks of the wire drawing machine, and taking into account the basic equation of the externally excited direct current motor, equations (1) and (2) may also be expressed as follows

basic equation of direct current motor:

$$n_1 = U_1/k_1\Phi_1, n_2 = U_2/k_2\Phi_2, n_n = U_n/k_n\Phi_n \quad (3)$$

where

$U_1 \dots U_n$ are the terminal voltages of the motors $m_1 \dots m_n$

$\Phi_1 \dots \Phi_n$ are the fluxes generated by the field windings of the motors $m_1 \dots m_n$

$k_1 \dots k_n$ are constants.

$$C_1 = K_1\Phi_1I_1, C_2 = K_2\Phi_2I_2 \dots C_n = K_n\Phi_nI_n \quad (4)$$

(1) and (2)

$$U_1 + U_2 + \dots + U_i + \dots + U_n = \Sigma U_1 \dots n = \text{constant} \quad (1')$$

$$\begin{aligned} I_1 &= I_1 & I_1 &= k'_1 I_1 \\ I_2 &= k'_2 I_1 & I_n &= k'_n I_1 \end{aligned} \quad (2')$$

In order to obtain the above-mentioned advantages, viz, automatic compensation, or to obtain a differential wire drawing machine, equations (1') and (2') must always be met. A similar wire drawing machine for which equations (1') and (2') are always met, is known, viz, a wire drawing machine with series-connected driving motors $m_1 \dots m_i \dots m_n$, such as described in the Belgian Pat. No. 481.842.

However, this known machine has important disadvantages, viz.:

In case of wire breakage during the drawing process, threading-up is accomplished, after welding the wire, by an appropriate change of the torques acting on the motors. This change is effected by altering the field current in the field windings of these motors. So, the torques connected to each motor for a certain stationary regime must be changed and readjusted in order to reobtain the stationary regime. This is a complicated and time-absorbing process.

In the case of series-connected driving motors, it is necessary to use special transformers for the classic motors (440 volts), and to develop special low tension motors; this is the most used solution.

In addition, since the current in series-connected motors is very high, the lives of the motors is prejudicially influenced. Indeed, the necessary power $P = U.I$. As U is generally low, a high current I is used.

The danger of racing of the motors in case of wire breakage is also a disadvantage. In case of breakage all motors stop, whereas one of the motors starts racing. In stationary regime, the total applied voltage U is distributed over the motors or a voltage U/n is applied to each motor.

Because all motors stop except one, the latter will try to reach such a speed that its E.M.F. is equal to the total voltage U or, in other words, this motor will try to run n times faster.

In the case of series fed motors, it is necessary to stretch the wire between the successive blocks so that the machine may start again after having been stopped when the wire hung loose or sagged between the successive blocks. This happens by a change of the torques acting on the motors. This change is effected by altering the field current in the field windings. Also this is a complicated and time-absorbing process.

Working with less passes than normally provided for the machine also entails important difficulties. For example, a principal n -hole machine from which three passes are eliminated. In case of series feed, each motor to be eliminated must be bridged by means of a contactor which must be able to deviate the large series current.

It is an object of the invention to provide a wire drawing machine of the aforesaid type wherein also equations (1') and (2') are always met and, moreover, wherein the aforesaid disadvantages of the known machines are eliminated.

Therefore, it is proposed that for a wire drawing machine of the aforesaid type, these direct current motors $m_1 \dots m_i \dots m_n$ are connected in parallel, whereby each motor $m_1 \dots m_n$ is provided with a self-controlled rectifier $G_1 \dots G_n$ for converting the feed from the alternating current system, so that each motor $m_1 \dots m_n$ is provided with a direct voltage output circuit $O_1 \dots$

$O_1 \dots O_n$ for the separation of the terminal voltages $U_1 \dots U_n$, whereby the output terminals of these transformers $O_1 \dots O_n$ are connected in series for summing up or obtaining $\Sigma U_1 \dots U_n$, and that the regulating mechanism of the assembly is provided with an adjustable direct current source U for the determination of a reference voltage U_R and, furthermore, with an amplifier P , whereby the input of the amplifier is determined by the difference $U_R - \Sigma U_1 \dots U_n$ and the output of this amplifier is transferred to the control circuit of the rectifiers $G_1 \dots G_n$ or is used as reference value I_R for the determination of the currents $I_1 \dots I_n$.

The regulating mechanism of a wire drawing machine according to the invention, of which the motors $m_1 \dots m_n$ are connected in parallel, is designed in such a way that when making a correction in order to meet equation (1') or $\Sigma U_1 \dots U_n = \text{constant}$, equation (2') is automatically met, or, in other words, in order to meet $\Sigma U_1 \dots U_n = \text{constant}$ (1'), a correction is made by changing the currents $I_1 \dots I_n$ in the motors $m_1 \dots m_n$ in such a way that equations (2') are always met. This is obtained by taking the output value of amplifier P as a reference value for the determination of currents $I_1 \dots I_n$ in the motors $m_1 \dots m_n$, or, in other words, this signifies that the control circuits of the rectifiers $G_1 \dots G_n$ are connected in parallel on the output of amplifier P .

In a wire drawing machine according to the invention, a switch $S_1 \dots S_n$ is provided between the output of amplifier P and the input of each control circuit of the rectifiers of the motors, and the control mechanism of each motor $m_1 \dots m_n$ is provided with a handle $H_1 \dots H_n$ having four positions, I (up), II (down), III (left), and IV (right), whereby these switches $S_1 \dots S_n$ and these handles $H_1 \dots H_n$ are mutually connected by means of known relay connections in such a manner that for any motor m_i , only motor m_i is energized in position I, all motors $m_1 \dots m_n$ in position II, all motors $m_1 \dots m_n$ up to m_i in position III, all motors $m_{i+1} \dots m_n$ up to m_n in position IV, and that, when released, each handle H_i automatically takes the zero position.

A wire drawing machine as set forth in the invention offers the following advantages:

When wire breakage occurs, wire threading after welding can be done by connecting only the motors that serve for carrying out this operation, since the control circuit of each motor can be easily interrupted. This happens by moving the handles $H_1 \dots H_n$ or in other words by controlling the switches $S_1 \dots S_n$. The torques $C_1 \dots C_n$ acting on these motors are no longer altered by a change of the current in the field windings. This considerably simplifies the service of the machine.

Because of the parallel feed of the motors, the three-phase alternating current system (380 volts) can be used without using transformers for the classic direct current motors (440 volts).

The parallel feed of the motors also permits maintaining the current in each motor at a low level, which is of importance for a long motor life.

In case of wire breakage, there is no danger for racing of the motors. A classic motor (440 volts) will maximally run 15 percent above its normal working speed, since the applied voltage can maximally be 510 volts in a three-phase alternating current system of 380 volts.

Since each motor $m_1 \dots m_n$ has a proper current control with its own time constant, the machine ac-

cording to the invention may run in with somewhat loose wires on various blocks. This saves time and difficulties when starting.

Working with a smaller number of passes than normally provided for the machine does not entail any difficulties. It is only necessary to interrupt the control circuit of the motors or blocks to be isolated.

The invention will now be described in greater detail, 10 with reference to the accompanying drawing, the single FIGURE of which is a circuit diagram of the machine as set forth in the invention.

The machine illustrated in the drawing is a non-slip non-accumulating continuous wire drawing machine

15 with adjustable back-pull containing n drawing dies $T_1 \dots T_i \dots T_n$ and n drawing blocks $W_1 \dots W_i \dots W_n$. Each block $W_1 \dots W_i \dots W_n$ is driven by a separate direct current motor $m_1 \dots m_i \dots m_n$ with external excitation. These motors $m_1 \dots m_n$ are connected in parallel. The nominal voltage of these motors is for example 440 volts. Each motor $m_1 \dots m_n$ is provided with a self-controlled rectifier $G_1 \dots G_n$ for converting the feed from the three-phase alternating current system, for example an alternating voltage of 380 volts. The rectifiers $G_1 \dots G_n$ are controlled by means of a thyristor circuit. It is assumed that for a certain stationary regime, the motors $m_1 \dots m_i \dots m_n$ should produce torques $C_1 \dots C_i \dots C_n$ at speeds $n_1 \dots n_i \dots n_n$. Except for a proportionality factor, these torques are determined by the product of the fluxes $\Phi_1 \dots \Phi_i \dots \Phi_n$ produced by the field windings $P_1 \dots P_i \dots P_n$ and the armature currents $I_1 \dots I_i \dots I_n$ or $C_i = k_1 \Phi_i I_i \dots C_i = k_i \Phi_i I_i$ and $C_n = k_n \Phi_n I_n$. The fluxes $\Phi_1 \dots \Phi_i \dots \Phi_n$ in the field windings $P_1 \dots P_i \dots P_n$ are determined by using the resistors $R_1 \dots R_i \dots R_n$ of these windings and the armature currents $I_1 \dots I_i \dots I_n$ in the motors by current amplification of the adjustment.

Each motor $m_1 \dots m_n$ is provided with a direct tension — direct tension transformer $O_1 \dots O_n$ for the galvanic separation of the terminal voltages $U_1 \dots U_n$ of the motors, whereby the output clamps of these rectifiers $O_1 \dots O_n$ are series-connected, so that except for a proportionality factor, the sum or $\Sigma U_1 \dots U_n$ is obtained.

45 The regulating mechanism of the machine is provided with an adjustable direct tension source U for the determination of a reference tension U_R , which corresponds to a certain sum of the speeds $n_1 + \dots + n_i + \dots + n_n$ or $\Sigma U_1 \dots U_n$.

50 Furthermore, the control mechanism is provided with an error amplifier P , whereby the input value of the amplifier is determined by the difference $U_R - \Sigma U_1 \dots U_n$ and the output value of this amplifier is transferred to the control circuit of the rectifiers $G_1 \dots G_n$. This means that the output value of the amplifier P is used as reference value I_R for the determination of currents $I_1 \dots I_i \dots I_n$ in the motors.

55 Switches $S_1 \dots S_i \dots S_n$ are provided between the output of amplifier P and the input of each control circuit of the motors. Moreover, each motor $m_1 \dots m_i \dots m_n$ is provided with a handle $H_1 \dots H_i \dots H_n$ having four positions, I (up), II (down), III (left), IV (right). The switches $S_1 \dots S_n$ and these handles $H_1 \dots H_n$ are connected by means of known relay connections in such a way that for any motor m_i only motor m_i is energized in position I, all motors $m_1 \dots m_n$ in position II, all motors m_1 up to m_i in position III, and all motors m_{i+1} up

to m_n in position IV. When released, each handle H_i automatically takes the zero position, or, in other words, the associated switch S_i is automatically opened.

The excitation current in the field windings $P_1 \dots P_i \dots P_n$ is supplied by source Y. This source Y is provided with an adjustable resistor R for the determination of the final machine speed.

It is evident that various embodiments of the invention are possible. So, the direct current motors $m_1 \dots m_n$ may be provided with a compound winding. Also, other relay connections may be provided between switches $S_1 \dots S_n$ and the associated handles $H_1 \dots H_n$ in order to obtain other controls from switches $S_1 \dots S_n$ in other handle positions.

What we claim is:

1. A plural stage processing assembly for a length of metal, comprising:
  - a. a plurality of metal deforming stations through which a length of metal is successively passed,
  - b. takeup and drawing means at each deforming station and in engagement with the length of metal,
  - c. a separate electrical driving motor connected to each of the takeup and drawing means,
  - d. motor speed measuring means connected to each motor for measuring the speed thereof and producing an output signal dependent on motor speed,
  - e. summing means to which the outputs of all of the motor speed measuring means are interconnected for producing a total motor speed signal representing the sum of all of the output motor signals,

f. power supply means for supplying electrical energy to each of the electrical motors and to which they are connected in parallel,

g. the power supply means having a variable electrical output which is dependent upon a control voltage supplied thereto,

h. the total speed output signal of the summing means being applied to the power supply means as a control voltage to control the electrical energy output to the electrical motors.

2. The plural stage processing assembly as set forth in claim 1, wherein:

- a. the power supply means is an amplifier through which alternating current is supplied,
- b. each of the electrical motors is a direct current motor,
- c. each of the motors has a self-controlled rectifier means connected between the source and the motor.

3. The plural stage processing assembly as set forth in claim 1, wherein:

- a. each metal deforming station is a wire drawing die,
- b. each of the takeup and drawing means is a drawing block.

4. The plural stage processing assembly as set forth in claim 1, wherein:

- a. automatic switch means is provided in each of the motor circuits for either energizing or de-energizing the motor.
